UNITED STATES PATENT OFFICE

2,516,665

LOOPER FOR LOCK-STITCH SEWING MACHINES

Anthon Le Roy Ambye, Andover, Mass., assignor
to L. O. Nichols, Newton, Mass., a firm

Application February 6, 1948, Serial No. 6,715

1 Claim. (Cl. 112—218)

1 My present invention is a novel and improved construction of a looper for use in sewing machines, which looper carries the lower thread to form a lock stitch in cooperation with the needle penetrating the work, in the well-known type of lock stitch sewing machine.

Heretofore, considerable difficulty has been found in such looper constructions, which were usually made of a single needle-like bar, usually curved and fitting in a shank and actuated to rock back and forth in a circular path to feed the lower line of thread to engage the thread loop formed by the needle as the needle penetrates the work and before it is retracted for the succeeding stitching action.

These loopers move or rock back and forth directly in the path of the needle and are often struck by the needle and broken, and hence require the stoppage of the machine, removal of the entire looper device, and replacement of the same.

My present improved construction obviates this difficulty to a large degree and provides a removable looper wherein the thread-carrying part only of the looper can be quickly removed and replaced.

Furthermore, by my present invention, this removal and renewal action of the thread-carrying bar of the looper is effected in a convenient position for the operator so that the replacement of a broken bar can be instantly effected, saving time in the stoppage of the work, preventing the necessity for adjustment of the shank portion of the looper in the actuating mechanism, and being instantly completed.

A further feature and advantage of my present invention consists in the economy and cheapness of renewing the relatively small part of the thread-carrying bar as distinguished from replacing an entire body portion, shank, and complete looper device. Such loopers being necessarily made of fine steel and of a precision construction, with a groove and eye of predetermined dimensions, which eye and thread-carrying recesses are drilled in the part apt to be so broken, involve very substantial expense. By my improved device, I replace only the thread-carrying bar which has formerly consisted in an integral part with the shank, my looper needle fitting firmly into a rigid and reinforcing construction for the thread-carrying bar so that the bar can resist to a high degree the impact of the needle and, hence, prevent to a considerable extent the breakage.

Thus, by my invention of a quickly removable

5 top bar in a looper, without disturbing the feeding and adjustment of the body and base portion of the looper in the rocking mechanism, I also insure a more accurate replacement of parts, as well as ease and efficiency from the operator's standpoint, and the speed of replacement of a broken looper.

Referring to the drawings: Fig. 1 is a top plan view; Fig. 2 is a side elevational view; Fig. 3 is a side elevational view partly in cross-section at a 90° angle with respect to Fig. 2; Fig. 4 is a plan view of a modification; Fig. 5 is a side elevational view; and

15 Fig. 6 is a view partly in cross-section at a 90° angle relatively to Fig. 5.

Referring to the drawings and to the forms shown in Figs. 1, 2, and 3, my present improved removable two-part looper construction comprises 20 a head 1 formed integral with a post 2 and a shank 3, the shank 3 being adapted to fit within the rocking mechanism of the sewing machine and with a flange 5 formed integrally between the post 2 and shank 3 to limit the fitting of the shank 3 in the rocking mechanism. The head 1 is, preferably, formed with a short lug or extension 8, which is tapped inwardly to receive a set screw 10, preferably of a typical socket head type, this set screw being threaded therein thru a correspondingly threaded portion 9 of the extension 8 and continued into the head 1 to intercept a transverse gored or bored opening 12, which opening is designed to receive the shank 15 of the looper bar 20.

30 35 This bar is also formed with a flange 21 constituting a bearing fitting on the side of the head 1 and said bar is further bored, as shown at 22, thru which the thread carried by the looper is roved, passing along thru a groove 24 lengthwise 40 of the bar and outwardly thru an eye 25 near a point 26.

Thus, in assembling the removable top bar 20 in the head 1, the set screw 10 is loosened, the bar 20 removed and a new bar instantly fitted, the set screw 10 tightened, and the looper ready 45 for use. These operations of loosening and tightening the set screw 10 can be quickly and readily performed and in a convenient position so that the operator is not unduly delayed and the work only momentarily held up when it is necessary to replace a broken or damaged looper bar 20.

50 In the forms shown in Figs. 4, 5, and 6, an offset upper bar is illustrated. In this form, the head 30 has a central bored opening to receive

the shank 31 of the looper bar 33, which bar has a bored opening 32 therethru permitting the thread to be roved therethru and along a groove 35 to the eyelet 36 near a point 37 of the looper bar 33. The flange 32 on the looper bar bears against the side of the head 30 and reinforces the looper bar 33 in this position. The head 30 is provided with an extension 38 threaded to receive a correspondingly threaded set screw 40 which can be tightened against the shank 31 and quickly releases or locks the bar 33 in position during replacement and renewal, as will be readily appreciated.

In this form, the head 30 has offset portions 44 and 45 formed with the shank 46, which latter is adapted to be fitted in a corresponding socket in the rock arm of the machine.

Thus it will be appreciated that my removable looper permits renewal of the breakable portion of the looper, viz., the top bar, by a quick, convenient, and easily operated replacement, when damaged or broken, and at a minimum of expense. The manufacture of the top bar 20 or 33 is a comparatively inexpensive manufacturing proposition as it is a short straight grooved bar with a shank and flange. The flange 21 in Figs. 1, 2, and 3, or 32 in Figs. 4, 5, and 6 constitute a stop to accurately fit the looper bar in the head and also to constitute a strengthening and torsion-resisting element, thus tending to withstand

breakage of the top bar from impact with the sewing machine needle or other damaging blow thereto.

Thus my removable looper is positively reinforced where it fits into the socket, by the bearing flange and the sturdy construction afforded by my design. Furthermore, this reinforcing feature is substantially at the point which was formerly the weakest part and where breakage 10 was most frequent in old style loopers.

I claim:

In a two-part removable looper of the kind described adapted for use in a lock-stitch sewing machine, comprising a head portion having a socket and an integral supporting post, the socket opening in said head formed to receive the shank of a removable thread-carrying looper bar, a transverse tapped opening communicating with said socket, and a set screw fitted in said tapped opening to removably secure the thread-carrying looper bar in said head.
